His Attorney.

UNITED STATES PATENT OFFICE.

ALBERT WHITE, OF LOWELL, MASSACHUSETTS, ASSIGNOR TO FREDERICK TAYLOR, OF SAME PLACE.

COAT-HOOK.

SPECIFICATION forming part of Letters Patent No. 501,452, dated July 11, 1893.

Application filed March 26, 1890. Serial No. 345,351. (No model.)

To all whom it may concern:

Be it known that I, ALBERT WHITE, a citizen of the United States, residing at Lowell, in the county of Middlesex and Commonwealth of Massachusetts, have invented a certain new and useful Improvement in Hat and Coat Hooks, of which the following is a specification.

My invention relates to hat and coat hooks and consists in such a hook constructed as hereinafter described, from a single wire, the construction being such as to combine economy of labor and materials required in producing the same, and to secure a hook of great strength and durability.

The accompanying drawing is a perspective view of my improved hat and coat hook.

The hat and coat hook herein described is formed from a single piece of wire A, and has a screw-threaded point a, at one end of the wire, in the usual manner, to enable said hook to be secured to a wall, cleat or other support, and near the other end of said wire has a loop a' which surrounds the portion of the wire near said point a. A part of said wire is formed into an upper hook H, having a horizontal shank-wire a², and, beyond said shank-wire, a laterally bent loop a³ which is curved upward, as shown, and has a considerable lateral extension to form a broad bearing for garments supported thereon. From the loop a³ the wire is carried back, at a⁴, for a distance, parallel with the shank a² and in the same plane, and is then bent downward at an angle, at a⁵, to form an inclined strut or brace B, to connect the upper hook H and the lower hook H'. At the lower end of the brace B, the wire is bent downward and forward to another loop a⁶ which forms the free end of the lower hook H' and which is spread laterally to form a broad bearing, as above-stated with reference to the loop a³. From said loop

a⁶ the wire is bent backward to the lower end of said brace B and then vertically upward to the loop a', to form a rest or back a⁷ which bears against the wall or other support of the hook. The lower hook H is double or formed of two portions of wire from the lower end of the brace B outward and the upper hook H is double or formed of two portions of wire 50 from the upper end of said brace to the end of said hook, and the back a⁷ of the hook is also double, the unthreaded end portion of the wire being preferably continued downward from the loop a' to the lower end of the 55 brace-wire B. Both members of the same hook H H' lie in the same surface laterally, that is, a line connecting two points, one in each member of the same hook, at equal distances from the free end of said hook will be 60 a horizontal line.

I claim as my invention—

A hook formed of a single piece of wire, one end of which is formed into an attaching-point, said wire being doubled upon itself 65 with an upwardly deflected loop to form a hat hook, the two members of which are in the same surface laterally, said wire from the rear end of one of said members being extended diagonally downward and then doubled upon 70 itself and curved to form a coat hook, the two members of which are in the same surface laterally, said wire from the end of one of said last-named members being extended vertically and around the shank of one member 75 of said hat hook, substantially as described.

In witness whereof I have signed this specification, in the presence of two attesting witnesses, this 28th day of February, A. D. 1890.

ALBERT WHITE.

Witnesses:
